(57) **CLAIM**

We claim the ornamental design for an electronic sight, substantially as shown and described.

DESCRIPTION

FIG. 1 is a front, right, top perspective view of an electronic sight wherein a cover on a lens is in an open position;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a front, right, top perspective view thereof, wherein the cover on the lens is in a closed position.
